PEBBLE HEAT-EXCHANGER

Robert R. Goins, Bartlesville, Okla., assignor to
Phillips Petroleum Company, a corporation of
Delaware

Application May 2, 1949, Serial No. 90,921

11 Claims. (Cl. 196—55)

1

This invention relates to improved pebble heat-exchanger design and to methods for effecting improved pebble and gas flow through such exchangers.

Pebble heat-exchangers are finding increasing favor in heating gases, such as air, nitrogen, etc., and in effecting various chemical processes in the vapor phase at elevated temperatures, especially hydrocarbon conversion processes. A conventional pebble heat-exchanger unit comprises a pair of vertically aligned pebble heat-exchangers connected by an axially positioned throat therebetween so as to provide for gravity flow of a contiguous stream of heat-exchange pebbles through the heat-exchangers. The pebbles in the upper heat-exchanger are contacted with hot combustion gas (or other hot gas) formed either in burners adjacent the base of the upper heat-exchanger or directly in the pebble mass itself. In this manner, the pebbles are heated to any suitable temperature above the required heating or reaction temperature in the lower heat-exchanger. The hot pebbles then gravitate to the lower chamber where they are contacted with the feed gas to be heated, treated, and/or reacted. The lower heat-exchanger usually has a funnel-shaped bottom converging to a pebble conduit which leads to the bottom of a pebble elevator or lift, usually of the bucket type, but which may be of the screw or air type. The elevator transfers the pebbles to a pebble chute above the level of the top of the upper heat-exchanger and this pebble chute or conduit leads into the upper portion of the upper heat-exchanger. This arrangement provides for continuously heating one section of a gravitating mass of pebbles and simultaneously continuously heating a gas in the lower section of the gravitating mass of pebbles and returning the cooled pebbles from the lower section of the gravitating mass to the upper section for repeating the cycle.

Pebbles utilized in the process and apparatus with which this invention is concerned are compact, spherical units consisting of alumina, mullite, zirconia, thoria, periclase, magnesia, high temperature alloys, such as Monel and inconel, and in some cases where temperature requirements are not too severe, metal such as iron, nickel, chromia, etc. In some processes, pebbles which will withstand temperatures upwards of 3000° F. are required and several good pebbles which function at these temperatures have been developed, one of the most suitable being mullite-alumina. Pebbles range in size from about $\frac{1}{8}$ " to 1" in diameter, but usually are within the range of $\frac{1}{4}$ " to $\frac{5}{8}$ ".

2

One of the chief difficulties of pebble heat-exchanger design is in designing the exchanger so as to obtain uniform pebble flow therethrough. Uniform pebble flow in the pebble heating chamber is important because without it, over-heating of some of the pebbles will occur while some sections of the gravitating pebble mass will be under-heated. Conventional design provides a cylindrical chamber with a hopper or funnel-shaped bottom which directs the flow of pebbles into a relatively narrow throat leading to the lower heat-exchanger. This corresponds to the general shape of the lower heat-exchanger also. It is found that pebble flow in this type of vessel is non-uniform through a considerable portion of the vessel. Stagnant flow areas exist chiefly around the juncture of the conical bottom and the cylindrical sides of the vessel, while extremely fast flow areas are found around the axis of the vessel. This non-uniform flow of contact material in a cylindrical vessel is emphasized in the U. S. Patent 2,430,669, to John A. Crowley. While the patent is not concerned with pebble heat-exchanger operation but rather with the flow of irregular particulate contact material, the flow problems are similar.

Another difficulty encountered in pebble heater operation and design lies in obtaining uniform gas flow upwardly through all sections of the heat-exchange chamber. Without uniform gas flow, it is obvious that there will be a lack of uniform heating, and especially treating or reacting of the gas in the lower chamber. In the conversion of hydrocarbons, particularly, uniform gas flow is paramount in order to control the exact contact time required in most conversion processes and especially processes which are effected at the high temperatures provided in pebble heater processes. It has been found that over-contacting or "soaking" of the hydrocarbon in the heat-exchanger results in complete cracking to coke and deposition of the same on both the pebbles and the interior of the chamber which has sometimes resulted in shutting down of the unit due to clogging of the pebble passageways with fragments of coke from the walls of the exchanger or agglomeration of the pebbles with carbon.

The principal objective of the present invention is to provide uniform pebble and gas flow in a system of pebble heat-exchangers. Another object of the invention is to provide uniform contact between gas and pebbles in a pebble heat-exchanger. A further object of the invention is to provide uniform gas-pebble contact with a minimum of pressure drop through the pebble bed. Other objects of the invention will become ap-

parent from a consideration of the accompanying disclosure.

The present invention provides a pebble heat-exchanger design which requires relatively short horizontal gas flow through the pebble bed and therefore permits the gas to traverse the whole horizontal cross-section of the bed on its way upwardly through the chamber. It also provides for the introduction of the gas to the pebble bed at a point above the area of stagnant flow so as to contact the pebble mass only in that section which is moving uniformly toward the pebble outlets as a preferred modification of the invention.

In order to improve the flow of pebbles through the heat-exchanger, the present design provides a relatively narrow pebble column above each pebble outlet. It has been found that in order to obtain any degree of uniformity of pebble flow, even in the upper section of the bed, the height of the bed must be at least one and one-half times the horizontal width of the bed in a vessel where the pebble outlet is positioned at the center of the bottom. By effectively dividing up the gravitating pebble mass into several narrow columns with a separate pebble outlet for each, the effective height of the column is increased and its width decreased, and it is therefore found possible to utilize the upper section of each column as a uniformly gravitating mass for contact with the contacting gas admitted at points above the bottom of the column. The uniformly gravitating section of the pebble bed in apparatus of the invention includes the upper three-fourths to seven-eighths of the bed. The high narrow columns of flowing pebbles provide maximum uniformity of flow without cutting down the effective width of the entire pebble bed and hence, the capacity of the unit. The effective narrowing of the pebble column is combined with the injection of contacting gas at points closer to the center of the column than is provided in conventional pebble heat-exchangers.

In order to more clearly understand the invention, reference is made to the drawing of which Figure 1 is an elevation, partly in section, of a two-chamber pebble heat-exchanger system or unit; Figure 2 is a horizontal cross-section of the heat-exchanger shown in Figure 1 taken on the line 2-2; Figure 3 is a vertical cross-section of a heat-exchanger taken on the line 3-3 of Figure 2; Figures 4 and 5 are horizontal cross-sections of other modifications of heat-exchangers.

Figure 1 shows a pair of pebble heat-exchangers 10 and 11 connected by connecting section 12. The unit is lined with a refractory 13 which may be of any suitable high temperature refractory composition, such as electric furnace alumina. Refractory columns 14 and 15 are positioned axially in each chamber so as to provide a somewhat annular pebble bed of narrow horizontal cross-section in relation to its height. Element 16 is a pebble chute connecting the top of the elevator and the upper portion of the interior of the upper pebble chamber through stack 17. The lower end of pebble chute 16 terminates in a plurality of short feeder tubes 18 which deliver pebbles to the center of the generally annular pebble bed 21 surrounding column 14. In a similar manner, pebble bed 22 in the lower chamber is supplied continuously by pebble passageways or throats 23 leading from the bottom of the upper chamber to the top of the lower chamber. Pebble passageways 24 are

positioned similarly in the bottom of the lower chamber and function to pass pebbles continuously into the hopper-shaped section 25 below the floor of the lower chamber. This hopper-shaped section converges pebbles to pebble conduit or chute 26 leading to the bottom of elevator 28 through pebble feeder 27. This feeder 27 may be any type of device used for feeding small particulate material through a conduit, such as a table feeder, a star wheel, a vibrator screen, etc. Elevator 28 is preferably of the bucket type but may be of the screw or gas lift type.

Conduits 29 and 31 positioned in the lower portion of each heat-exchanger serve to introduce gas in heat-exchange relation with the pebbles in the chambers. The exact arrangement of these conduits can best be seen in the other figures of the drawing. A combustible gas introduced through conduits 31 is introduced to chamber 10 where it is burned. The combustion gas passes upwardly through the chamber, heating the pebbles therein, and out through stack 17. In the lower chamber the feed gas to be heated, treated, and/or reacted is introduced through conduits 29 and the effluent is taken off through an opening 36 in the dome of the chamber into a gas space 34 in the center of connecting section 12, from which it is removed through one or more openings 35 in the wall of the gas space. For the sake of simplicity, control means, motors, recorders, blowers, etc., have not been shown.

An essential feature of the design of the unit lies in the relatively narrow elongated pebble throats or passageways 23 in Figure 1 which function as valves when full of pebbles to minimize the flow of gas between the upper and lower heat-exchangers. In order for these pebble passageways to obstruct the flow of gas between chambers, the whole unit from pebble inlet nozzles or tubes 18 to pebble feeder 27 must be maintained full of a contiguous compact bed of pebbles. While pebble passageways 23 and 24 should be relatively narrow, they should be sufficiently large in diameter to provide free flow of pebbles therethrough and in any case should be several pebble diameters across.

Figure 1 shows a plurality of pebble feeder pipes 18. Any convenient number of these may be utilized so as to properly distribute the pebbles around the bed. While this arrangement provides better pebble distribution over the top of the bed than would be provided without the use of these tubes, the apparatus will function satisfactorily if all of the pebbles are delivered at a central point from the mouth of pebble chute or conduit 16. Likewise, it is not essential to the design of the apparatus to position the lower end of conduit 16 axially inside of stack 17. However, this arrangement utilizes the heating effect of the combustion gas to a maximum by heat-exchange with the incoming pebbles which are at their lowest temperature in the system. Because of the lower temperature existing in the upper section and stack 17 of the upper heat-exchanger, elements 16 and 18 may be fabricated of metal, such as stainless steel, or even less expensive metal, which is non-corrosive and will withstand temperatures up to 800 to 1000° F.

The design of Figure 2 is that of a heat-exchange chamber dividing the pebble bed into four symmetrical columns grouped around the four pebble outlets 23 and bounded by the cylindrical refractory wall 13, refractory ridges 32, and

the center column 14. These refractory ridges 32 preferably extend upwardly from the floor of the chamber to the dome thereof so as to provide a pebble column of uniform horizontal cross-section. These arcuate ridges curve inwardly so as to narrow the width of the pebble column between each pair of ridges and between each ridge and the center column 14 and to withstand the horizontal thrust of the pebbles against the wall of space 30. Ridges 32 are preferably hollow at their lower extremity as shown in Figure 3 where hollow space 30 is shown as a combustion chamber into which a combustible gas is introduced through line or conduit 31. Openings 33 in the upper part of the combustion chamber (or gas collecting space when this design is used for the lower heat-exchanger) lead slightly downwardly into the pebble chamber and radially from the arcuate section or ridge so as to properly distribute the gas over the full cross-section of the pebble column. Gas passageways 33 are directed downwardly into the pebble chamber so as to prevent the flow of pebbles into combustion chamber 30. Element 35 is the effluent outlet shown in Figures 1 and 2 for removing gas from the lower pebble heat-exchanger. While a single conduit is shown, any suitable number of these gas take-off conduits may be used.

Figure 4 shows a modification of the invention without the center column. This design effectively divides the heat-exchange chamber and pebble bed into three vertical columns bounded by the cylindrical refractory lining of the chamber, the arcuate sections, and an imaginary surface extending from the center of each arcuate section to the axis of the chamber. Pebble outlets 23 are positioned at the approximate center of the bottom of each column so as to withdraw pebbles uniformly therefrom, and improve the pebble flow through the entire cross-section of the heat-exchange chamber.

Figure 5 illustrates another modification of the invention without the center column which permits direct introduction of a combustible gas to the pebble bed and burning of the combustible mixture on the surface of the pebbles in the lower portion of the chamber. This unit may also be operated by introducing hot combustion gas directly through line 31, but this method of operation is not so efficient because the hot combustion gas must be formed outside the chamber and some loss in heat will be involved. Where it is preferred, the heat-exchangers shown in the first four figures may be modified in the same manner as shown in the design of Figure 5 so that the contacting gas is introduced directly from outside the chamber through the inwardly extending ridges or arcuate sections. The combustion or gas space 30 shown in Figures 2, 3, and 4 is not so essential in the gas treating chamber or lower heat-exchanger although this type of gas collecting space may be utilized in the distribution of the gas to be treated to the pebble bed in the lower heat-exchanger.

A significant feature of the invention and of all of the modifications shown is the introduction of the contacting gas in either chamber at a level above the bottom of the chamber, as shown in Figure 3, through holes 33 in the refractory wall of the combustion space. Irrespective of the design of the heat-exchange chamber, there will always be a small stagnant flow area in the bottom of the chamber between the pebble passageways and the vertical wall or walls of the chamber. In the heating chambers of the invention

the uniform pebble flow section occupies at least the upper three-fourths and up to seven-eighths or more of the pebble bed. By introduction of the gas into contact with the gravitating mass of pebbles above this stagnant area, contacting is effected only in the uniform pebble-flow section of the bed which results in more nearly uniform contact time between gas and pebbles in various sections of the bed.

10 The effective narrowing of the pebble bed provided by the invention is obvious from a consideration of the designs shown in the various figures of the drawing, and this is effective in reducing the horizontal distance which the contact gas must travel in order to traverse the entire cross-section of the pebble bed. This horizontal distance is shortened by application of the invention to a pebble heat-exchanger of any given diameter.

20 Pebble heat-exchangers of the type with which this invention is concerned have utility in a wide variety of heat-exchange processes which require the heating, treating, and/or reaction of a gaseous feed. The application of M. O. Kilpatrick, Serial No. 761,696, filed July 17, 1947, describes the detailed operation of a pebble heat-exchanger unit in the conversion of hydrocarbons. The application of C. W. Perry, Serial No. 677,357, filed June 17, 1946, now U. S. Patent No. 2,596,507, 25 shows the use of pebble heat-exchangers in the synthesis of HCN from NH₃ and carbon-containing gases. The application of Sam P. Robinson, Serial No. 665,673, filed April 29, 1946, now U. S. Patent No. 2,551,905, illustrates the use of pebble heat-exchanger apparatus in the desulfurization of gases, particularly hydrocarbon gases. The use of pebble heat-exchangers in the synthesis of carbon disulfide from hydrocarbon and sulfur-containing gases is disclosed in the application of Sam P. Robinson, Serial No. 651,293, filed March 1, 1946. The heating of air for high temperature use in the fixation of atmospheric nitrogen in a pebble heat-exchanger is disclosed in the application of Sam P. Robinson, Serial No. 767,300, filed August 7, 1947. The process of this last application illustrates the use of a heating gas other than combustion gas for heating the pebbles in the upper heat-exchanger. In the process referred to, air heated in the lower heat-exchanger is mixed with fuel and burned in a high temperature furnace to produce a temperature of approximately 4000° F. so as to effect the fixation of nitrogen and, in order to prevent decomposition of the product, the hot effluent is immediately passed through the upper heat-exchanger in contact with relatively cold pebbles, thereby heating the pebbles and quenching the product effluent from the reaction in the furnace. The hot pebbles gravitate to the lower heat-exchanger and are there contacted with atmospheric air so as to pre-heat the air for the fixation process.

45 50 55 60 65 70 75 The instant invention is applicable to the processes to which the applications just referred to relate. Since the pebble heat-exchanger disclosed provides uniform pebble flow and gas flow, it is particularly applicable to the conversion of hydrocarbons and to chemical processes which require short, specific reaction times. In hydrocarbon conversion processes involving dehydrogenation and cracking to specific products without over-cracking, the present invention offers particular utility.

I claim:

1. A pebble heat-exchanger for effecting heat-

exchange between a gravitating bed of pebbles and a gas, comprising a refractory-lined upright closed cylindrical vessel enclosing a heat-exchange chamber of symmetrical generally circular horizontal cross-section modified by the inward projection of several vertical ridges uniformly spaced on the inner wall thereof extending from the bottom upwardly into the upper section of said chamber so that vertical radial planes passing thru the center of the ridges divide the chamber into a plurality of contiguous vertical columns; gas inlets in each of said ridges in the lower portion thereof, the remaining portion of the ridges being imperforate; a refractory floor in said chamber; an axially positioned refractory column extending upwardly from said floor into the upper section of said chamber forming an inner wall for the gravitating pebble bed; symmetrically arranged pebble outlets in said floor spaced alternately with respect to said ridges and centrally with respect to the bottom area of said columns so as to provide maximum uniformity of pebble flow; and gas outlet and pebble inlet means in the top of said vessel.

2. The apparatus of claim 1 in which the gas outlet means comprises an axially disposed stack and said pebble inlet means comprises a smaller conduit concentric with said stack at least along its lower end thereby forming an annular gas passageway around said conduit extending into said chamber a minor portion of the chamber length so as to provide a pebble-free gas collecting space in the upper portion of said chamber in communication with said stack; and a plurality of uniformly spaced pebble delivery tubes sloping downwardly and laterally from the lower end of said conduit to loci midway between the upper end of said refractory column and the inner wall of said vessel.

3. The apparatus of claim 1 in which said ridges are hollow at the lower end only so as to provide a combustion zone therein in communication with said heat-exchange chamber through said gas inlets and having gas inlets thereto from outside said vessel.

4. The apparatus of claim 1 in which said ridges are arcuate in horizontal cross-section.

5. Pebble heater apparatus comprising a pair of superposed cylindrical, refractory-lined, gas-solid heat-exchangers in spaced apart relation, each enclosing a heat-exchange chamber of symmetrical generally circular horizontal cross-section modified by the inward projection of several vertical ridges uniformly spaced extending upwardly from the bottom thereof into the upper section of said chamber so that vertical radial planes passing thru the center of the ridges divide the chamber into a plurality of contiguous vertical columns; a refractory floor in each of said chambers having several symmetrically arranged pebble outlets therein disposed alternately around the chamber with respect to said ridges in the bottom of said chamber and centrally with respect to the bottom area of said columns so as to provide for maximum uniformity of pebble flow through the chamber; a vertical refractory column of minor horizontal cross-sectional area compared to the corresponding area of said floor extending upwardly into the upper section of each said chamber from the floor thereof; several pebble inlets in the top

of the lower chamber correspondingly positioned to the pebble outlets in the floor above and in open communication therewith providing unobstructed pebble flow between chambers; gas inlets to said chambers in the lower portion of each of said ridges, the remaining portion of the ridges being imperforate; a gas outlet in the top of each chamber; a pebble inlet in the top of the upper chamber; a hopper-shaped pebble chamber below said lower chamber communicating with the pebble outlets in the floor directly above and converging to a pebble conduit; and elevator means communicating with said pebble conduit and with the pebble inlet in said upper chamber.

15 6. The apparatus of claim 5 in which the ridges in said upper chamber are hollow at the lower end thereof so as to provide a combustion zone in communication with said chamber through said gas inlets and having gas inlets thereto from outside said vessel.

7. The apparatus of claim 5 in which the ridges in said upper chamber are hollow at the lower end thereof so as to provide a combustion zone in communication with said chamber through said gas inlets and having gas inlets thereto from outside said vessel.

20 8. The apparatus of claim 5 in which said ridges are arcuate in horizontal cross-section.

9. The method of effecting heat-exchange between a gravitating compact bed of refractory pebbles and a gas which comprises gravitating said pebbles through a vertical symmetrical generally annular heat-exchange zone surrounding a vertical cylindrical zone closed to the flow of 30 pebbles; withdrawing pebbles from the bottom of said zone through several pebble passageways spaced symmetrically in said bottom and midway between said cylindrical zone and the outer boundary of said heat-exchange zone so as to 35 provide uniform pebble flow in at least the upper three-fourths of said zone; introducing gas at a different temperature than the temperature of said pebbles to said zone in the lower portion of the uniform pebble flow section at regularly 40 spaced points around the periphery of said heat-exchange zone; passing said gas inwardly and upwardly over the entire horizontal cross-section of said zone in direct contact with said pebbles in heat-exchange relation therewith; and 45 recovering said gas from the upper section of 50 said zone.

10. The process of claim 9 in which said gas is hot combustion gas and said pebbles are heated thereby and thereafter contacted in a subjacent zone with a cooler gas so as to heat the same.

11. The process of claim 10 in which said cooler gas is a hydrocarbon and conversion of said hydrocarbon is effected.

ROBERT R. GOINS.
